DRINKING GLASS

Alexander Sloan, Cumberland, Md.

Application February 1, 1949, Serial No. 616

Term of patent 14 years

(Cl. D36—8)

To all whom it may concern:

Be it known that I, Alexander Sloan, a citizen of the United States, residing at Cumberland, in the county of Allegany and State of Maryland, have invented a new, original, and ornamental Design for Drinking Glasses, of which the following is a specification, reference being had to the accompanying drawing, forming part thereof.

I claim:

The ornamental design for a drinking glass, substantially as shown.

ALEXANDER SLOAN.
